UNITED STATES PATENT OFFICE.

JOHN E. MUHLEFELD, OF SCARSDALE, NEW YORK.

LOCOMOTIVE-TENDER.

1,262,231.

Specification of Letters Patent. Patented Apr. 9, 1918.

Application filed December 2, 1913, Serial No. 804,193. Renewed March 27, 1917. Serial No. 157,846.

To all whom it may concern:

Be it known that I, JOHN E. MUHLEFELD, of Scarsdale, in the county of Westchester and State of New York, have invented a certain new and useful Improvement in Locomotive-Tenders, of which improvement the following is a specification.

My invention more particularly relates to tenders for locomotives which burn pulverized fuel, and its object is to provide means for the storage of fuel of such character and of water, by which condensation on, or sweating of, the fuel receptacle, and resultant interference with the free flow of fuel are prevented; obstruction of said receptacle by pockets or projections avoided; and facilities afforded for the conveyance of fuel to desired points of delivery on the locomotive, without liability to arching over or packing of the fuel before reaching the conveying means.

The improvement claimed is hereinafter fully set forth.

In the accompanying drawings: Figure 1 is a vertical longitudinal central section through a locomotive tender, illustrating an application of my invention; Fig. 2, a vertical transverse section through the same, on the line *a a* of Fig. 1; Fig. 3, a similar partial section, illustrating a structural modification; and, Fig. 4, a side view, in elevation, of the fuel receptacle, detached.

My invention is herein exemplified as applied in a tender, the frame, 1, of which is of the ordinary construction, and which is supported on two swiveling trucks, 2, and having a tank, 3, the front wall, 3^a, of which is forwardly and downwardly inclined to a water bottom, 3^b. The tank also has forwardly extending lateral extensions, 3^c, which are inwardly and downwardly inclined on their inner sides, so as to be of substantially triangular section. There is thus provided, at the front of the tank, a longitudinal recess, the rear and side boundaries of which are downwardly and inwardly inclined, and which is open at its top and front. While my invention is desirably applicable in connection with a tank of this form, it is not limited thereto, and the fuel receptacle, hereinafter described, may be located in a recess formed in a water tank of circular or of D section, if desired.

The forward recess above described, of

the tank, is occupied by a fuel receptacle, 4, of stout plate or sheet metal, which, in the instance shown, is fitted removably in the space above the water bottom, 3^b, the rear and lower side walls of the receptacle being inclined in directions parallel with the front wall of the water tank and with the inner walls of the forward lateral extensions thereof, respectively, and the bottom being flat, in conformity with the top wall of the water bottom. All the open space at the forward end of the tank is thus rendered available for fuel storage, and the inclination of the rear and side walls of the fuel receptacle, together with the absence of pockets, projections, or reentrant angles enables the fuel contained in the receptacle to be carried by gravity to the bottom thereof, without tendency to obstruction in its downward traverse. The top of the fuel receptacle is preferably transversely curved or arched, and is provided with one or more openings, 4^a, controlled by hinged doors or lids, 4^b, said openings being of proper dimensions to admit of the supply of fuel to the receptacle, or of the entrance of an operator thereinto, if desired. A removable fuel receptacle, as above described, is desirably applicable in tenders of existing construction, but in new constructions it may, if desired, be permanently connected to the water tank.

The upper portion of the fuel receptacle is made slightly narrower than the lower portion, so as to provide room for the attachment of lateral running boards, 5, above which hand rails, 6, are connected to the receptacle, facilities being thereby provided for an operator to pass from one end to the other of the tender. Plates, 7, having eyes, 7^a, at their upper ends, are secured to the sides of the fuel receptacle, above the running boards, for the connection of hooks for lifting the receptacle out of, and returning it to, its position on the tender by the operation of a crane.

In order to prevent the condensation of moisture or vapor on, and the consequent "sweating" of, the fuel receptacle, which would tend to interfere with the free downward flow of pulverized fuel, a lagging or coating of heat insulating material, 8, is interposed between the outside of the receptacle and the tank. The portion of the fuel receptacle which extends above the

tank may be, as shown, similarly cased, to prevent possible sweating from difference of temperature between the outside atmosphere and the interior of the tank. Under certain 5 climatic conditions, the protection of the upper portion of the receptacle by insulating material may not be necessary.

Pulverized fuel is carried from the bottom of the fuel receptacle to a desired point of 10 delivery on the locomotive, by one or more conveyers, 9, three being shown in this instance, which are fitted to be rotated in longitudinal channels, 9^a, located on or adjacent to the bottom of the fuel receptacle. The 15 conveyers may be either of the screw type, as shown, or of any other suitable known form. In order to prevent the arching of fine fuel, which would prevent its free supply by gravity to the conveyers, upwardly 20 extending inclined guides, 10, are interposed between the conveyer channels, said guides meeting at their tops, and each extending therefrom to one side of a conveyer channel. The inclined side walls of the fuel receptacle 25 are similarly related to the adjacent conveyer channels. A vertical separating plate, 11, is fixed above, and in substantially the axial plane of, each of the screw conveyers, and extends to or near the level of the tops 30 of the guides, 10. The separating plates prevent the formation of semi-circular arches above the conveyers by the packing of the fuel, and so far reduce the spaces in which arching of the fuel could take place, 35 that tendency to packing is overcome by the weight of the fuel and the jarring of the tender in service.

In the structural modification shown in Fig. 3, the bottom of the fuel receptacle, instead of being flat, as in the construction 40 above described, is formed of a plurality of plates connected one to another at their tops and connected to the conveyer channels, 9^a, at bottom. Said plates, in addition to their 45 normal function of forming the bottom closure of the fuel receptacle, act as guides for the fuel to the conveyers, similarly to the separate plates before described, and the spaces between their outer sides may, if desired, be utilized to increase the water capacity 50 of the tank, by forming the top wall of the water bottom thereof with corresponding inclines.

I claim as my invention and desire to secure by Letters Patent:

55

1. In a locomotive tender, the combination of a frame, a tank supported thereon and having a longitudinal open space extending rearwardly from its front end, a fuel receptacle fitting into said space having a floor, 60 side walls, front and rear walls, and a lid or cover, an opening in the forward wall, and fuel conveying means adjacent the floor controlling said opening.

65

2. In a locomotive tender, the combination of a frame, a tank supported thereon and having a longitudinal open space extending rearwardly from its front end, an inclosed fuel receptacle provided with an outlet fitting into said space, and fuel conveying 70 means adapted to move fuel to said outlet and to control said outlet.

70

3. The combination with a locomotive tender frame and tank of an inclosed pulverized fuel containing receptacle provided 75 with an outlet, and fuel discharging means for discharging the fuel through and controlling said outlet.

75

4. In a locomotive tender, the combination of a frame, a tank supported thereon and having a longitudinal open space extending rearwardly from its front end, a fuel receptacle fitting removably in said recess, and a lagging of heat insulating material interposed between the fuel receptacle and the 85 tank.

80

5. In a locomotive tender, the combination of a frame, a tank supported thereon, a fuel receptacle fitting removably in a recess in said tank, lateral running boards fixed to 90 said fuel receptacle, and attachments fixed to said receptacle for connection to a hoisting and lowering mechanism.

90

6. In a locomotive tender, the combination of a frame, a tank supported thereon, a fuel receptacle fitting in a recess in said tank, a conveyer for transferring fuel from said receptacle to a point of delivery forward thereof, inclined longitudinal guide plates located on opposite sides of said conveyer, 100 and a vertical separating plate extending longitudinally above said conveyer.
